UNITED STATES PATENT OFFICE.

EPHRAIM BURDICK, OF CLEVELAND, OHIO.

ONION-TOPPING MACHINE.

1,217,269.

Specification of Letters Patent. Patented Feb. 27, 1917.

Application filed June 12, 1915, Serial No. 33,710. Renewed January 24, 1917. Serial No. 144,309.

To all whom it may concern:

Be it known that I, EPHRAIM BURDICK, a citizen of the United States, residing at Cleveland, in the county of Cuyahoga and 5 State of Ohio, have invented a new and useful Onion-Topping Machine, of which the following is a specification.

The object of my invention is to provide a novel machine for effectively topping 10 onions without bruising the onions; to provide novel means for feeding the onions through the machine; and to provide novel combinations and arrangements of parts in such a machine.

15 I attain the objects of my invention by the mechanism illustrated in the accompanying drawings, in which—

Figure 1 is a side elevation; Fig. 2 is a top plan with the chutes removed; Fig. 3 20 is an end view; Fig. 4 is a transverse sectional view; and Fig. 5 is a detail of modified or improved means for driving the cutting mechanism.

Like characters of reference indicate like 25 parts throughout the several views.

Referring to the accompanying drawings, I provide a frame 1, mounted on end supports 2. Carried by the end supports 2 are rollers 3 and 3', on which a freely revoluble 30 spiral drum is mounted. The drum is constructed of heavy spirally wound wire, as shown, and provided with a plurality of longitudinal ribs 5, spaced like distances apart and secured to the interior of the drum 35 in any suitable manner. In the machine illustrated, three ribs 5 are used. They carry the onions along toward the cutting mechanism as the drum revolves. At one side of the frame a beam 7 extends longitudinally 40 of the machine. On it is mounted a fixed cutter blade 6', and on blade 6' is mounted a reciprocating cutter blade 6, having means connected therewith for driving it from the roller 12 or bevel gear 12^a. As seen in Fig. 45 2, it consists of a rod 8, operatively connecting blade 6 to bell crank 9, which in turn is operatively connected by pitman 10 to wrist pin 11 on pulley 12. An improved or modified means for driving the cutting mechanism is illustrated in Fig. 5, comprising a 50 pitman 8^a connecting blade 6 with a rotating disk 9^a, which in turn is connected by gear rod 10^a and small gear 11^a with a large gear 12^a, the latter being mounted on the

end support 2, similarly to roller 12, and 55 replacing roller 12, as will be clearly understood by reference to Figs. 5 and 2.

Pulley 12 is operatively connected by belt 13 to pulley 14, mounted on shaft 15, which extends the full length of the machine. It 60 is within the contemplation of my invention to substitute sprockets and chains in lieu of belts and pulleys wherever desirable. Shaft 15 is provided with end pulleys 19 and 20, driven by belts 17 from pulleys 18 65 on the ends of roller 3, which in turn is operated by means of crank 16. It is within the contemplation of my invention to substitute power instead of hand driving means, the machine in such case being driven by a 70 gasoline engine operatively connected with the machine in a suitable manner.

Adjoining pulley 19 is a cam roller 21 in the face of which is a cam groove 22. Adjoining the pulley 20 is a pulley 23 carrying 75 a belt 24 mounted on a pulley 25 on the end of a topping finger roller 26, which is carried by a shaft 27. Shaft 27 extends for some distance beyond the end of the frame at each end of the machine, to allow for a 80 sliding movement of the shaft. Between beam 7 and cross member 37 of the end support 2 is a brace 29, to which is pivoted at 28, a lever 30, one end of which carries a pin 31 which rides in the cam slot 22 of the 85 cam roller 21. The opposite end of the lever 30 is provided with a hooked end 38, which engages a recessed portion 32 of the finger roller 26. A spring 33 is mounted on the opposite end support 2 and extends upwardly and engages the shaft 27 of the roller 26 to assist in returning roller 26 to its forward position. Roller 26 is provided with spaced fingers, of which there may be one or more sets, in alignment, as illustrated, 95 adapted to push the tops of the onions through the spaces between the spirally wound wire which forms drum 4. The topping fingers are preferably made of flexible material, such as pieces of hose, which prevents any bruising of the onions. A suitable supply chute 35 is provided at the head end of the machine, and a suitable discharge chute 36 is provided at the lower end of the machine, to facilitate the supply and discharge of the onions. The drum of the machine is suitably timed in its revolutions to the revolutions of the finger roller, so that 100 105

the fingers will not conflict with the ribs of the drum.

The operation of the machine will be apparent from the foregoing description in connection with the drawings. Its power is supplied by suitable means to operate roller 3. This may be by hand power applied to crank 16, or by an engine operatively connected with the shaft in some suitable manner. Operation of roller 3 causes the spiral wire drum 4 to revolve, due to the weight of the drum resting on rollers 3 and 3'. Roller 3' is loosely mounted. Pulleys on shaft 15 are driven from roller 3, thus revolving the cam roller also mounted on shaft 17, and also revolving topping finger roller 26, which is driven by belt 24. The reciprocating cutter blade which with the stationary blade tops the onions, is driven by suitable means from a pulley 12, as illustrated in Fig. 3, or from a sprocket gear 12^a, as illustrated in Fig. 5. In the former instance a rod bell crank and pitman operatively connect with roller 12. In the latter case, a pitman, disk, gear rod, and bevel gears, the latter preferably driven by a sprocket, replace the first mentioned mechanism. The essential function of the two mechanisms is alike in its ultimate object. Member 12 (or 12^a as the case may be) is in turn driven from shaft 15 by means of pulley 14 and belt 13. It is of course within the contemplation of my invention to substitute chains and sprockets in lieu of belts and rollers.

Revolution of cam roller 21 causes pin 31 to ride in slot 22 and oscillate lever 30 and in turn causes finger roller 26 to move longitudinally of the machine, returning to its position nearest the head end of the machine at the completion of each revolution, under the pressure and assisted by spring 33 at the end of shaft 27, as illustrated in Fig. 1. The spirals of drum 4 allow the fingers 34 of the finger roller 26 to pass in between them, as shown in Fig. 4, to push the heads of the onions down through the drum, the onions being carried forward into position to engage with knives 6 and 6' by contact with ribs 5, which extend longitudinally of drum 4, and are spaced apart at suitable intervals to avoid fingers 34.

What I claim is:

1. An onion topping machine comprising a supporting frame; opposite rollers; a crank for turning one of the rollers; a drum formed of spirally wound wire and having one or more longitudinally-disposed interior ribs the drum being freely revolvable on the rollers and operated by gravity from the driven roller; a cam and cam shaft operatively connected with and driven by the driven roller; a revolving topping finger having sets of spaced fingers adapted to project between the spirals of the drum to press the onion tops into pendent position; a

pivoted cam-guided member operatively connected with the finger roller to move same longitudinally synchronously with the travel of the drum spirals; a spring to return the roller to its position at the head end of the machine; a fixed cutting blade positioned to engage the pendent onion tops; a superposed reciprocally moving cutter blade; and means for reciprocating the cutter blade, the aforesaid means being operatively connected with driving means actuated from the cam shaft, substantially as set forth.

2. In an onion topping machine, a drum formed of spirally wound wire and having one or more longitudinal ribs secured to its interior portion, a driven roller supporting and causing the drum to revolve, a revoluble and reciprocally slideable roller having series of spaced fingers adapted to project intermittently between the spirals of the drum to press the onion tops into pendent position; cam guided means for reciprocally moving the finger roller; means operatively connected with the roller driving the drum to drive the topping-finger roller; means positioned exterior to and in proximity with the spiral drum to cut the pendent tops of onions as the drum is revolved; and means operatively connecting the aforesaid cutting means with the driven roller, whereby circular is transformed into reciprocating motion for the purposes set forth.

3. In an onion topping machine, a longitudinally ribbed revolving drum adapted to receive the onions, cutting means positioned exterior to and in proximity with the drum to engage the pendent tops of onions, means adapted to intermittently project between spirals of the drum and press onion tops into a pendent position and means for driving the aforesaid mechanism.

4. In an onion topping machine, a spiral wire drum, means moving synchronously with the spirals and positioned to project therebetween to press the tops of onions to a pendent position; means for revolving the drum; means for synchronously actuating the means for pressing tops to pendent position through the drum spirals; cam-governed means for reciprocating the aforesaid means to engage between spirals of the drum at each revolution; and means for cutting the tops from the onions as the drum revolves.

5. In an onion topping machine, a freely revoluble spiral wire drum having one or more longitudinal ribs, means for causing the drum to revolve; means adapted to project between spirals of the drum at predetermined intervals to press onion tops into pendent position; means operatively connected with the drum-actuating means to operate the onion-top engaging means; cutting blade mechanism positioned exterior to and in proximity with the spiral drum to

cut the pendent tops of onions; and means for reciprocating the aforesaid cutting mechanism.

6. In an onion topping machine, a drum, 5 rollers revolvably supporting the drum, means for driving one of the rollers, a finger-roller adapted to engage onion tops in the drum, means operatively connecting the finger roller with the roller driving the drum 10 to synchronously revolve those members,

means positioned in proximity to the drum to top the onions, and means operatively connected with the driven roller for reciprocating onion-topping means, substantially as set forth.
